M. T. Dinswell.

UNITED STATES PATENT OFFICE.

GEORGE H. RIVES, OF NEW YORK, N. Y.

ANTISKID DEVICE FOR SHOE HEELS.

Application filed June 20, 1919. Serial No. 305,504.

To all whom it may concern:

Be it known that I, GEORGE H. RIVES, a citizen of the United States, and a resident of New York, in the county of New York 5 and State of New York, have invented a certain new and useful Improvement in Anti-skid Devices for Shoe Heels, of which the following is a full, clear, and exact specification.

10 This invention relates more particularly to a class of devices adapted to be used in conjunction with the footwear of persons.

My invention has for its object primarily to provide a device designed to be applied 15 especially on the heels of shoes, boots and other footwear of persons so that the wearer when walking on slippery highways will be prevented from slipping. The invention consists essentially of a flexible supporting 20 band of a size to adapt it to be removably disposed around a shoe heel, and this band is preferably formed of two diverging sections and a transverse section. The transverse section may be of a length correspond-

25 ing approximately to the length of the straight edge of the shoe heel, while each of the diverging sections are of lengths corresponding substantially to one-half of the curved edge of the heel, and the opposed 30 ends of the sections of the band may be movably connected by rings. To the central parts of both of the diverging sections are held the ends of one or two spaced flexible anti-skid or line elements which depend

35 from the band in parabolic fashion for being disposed crosswise of the underside of the heel. To the central parts of both of these line elements is held one end portion of a third flexible anti-skid or line element having its second end held to the central part 40 of the transverse section of the supporting band, and this third line element also depends from the band so as to be disposed on the underside of the heel angularly with 45 respect to the pair of transverse line elements. Thus these anti-skid elements serve to engage the surface of the highway on which the wearer of the device may be walking to prevent slipping.

50 Another object of the invention is to provide means for detachably fastening the band with the flexible anti-skid elements to the heel of a shoe; and a further object of the invention is to provide an anti-skid 55 device which may be made in any desired size to fit different types of shoe heels.

With these and other objects in view, the invention will be hereinafter more fully described with reference to the accompanying drawing forming a part of this specification 60 in which similar characters of reference indicate corresponding parts in all the views, and will then be pointed out in the claim at the end of the description.

In the drawing, Figure 1 is an elevation 65 of a shoe showing one form of anti-skid device embodying my invention applied thereto, and

Fig. 2 is an enlarged fragmentary view 70 showing the device in perspective as used in conjunction with a shoe heel.

The anti-skid device has a supporting band 10 which may be of any desired shape, though the band is preferably composed of two side sections 11, 12 and a transverse section 13, and this band may be somewhat the shape of a triangle whereby the side sections diverge with relation to each other, while the transverse section is disposed between the widely spaced ends of the diverging sections. The sections of the band 10 may be made of metal chains, or may be made of other flexible material to adapt it to be removably arranged around a shoe heel, as 14, in a manner so that the transverse section 75 will be crosswise of the straight edge, as 15, of the heel, while the diverging sections are arranged upon the curved edge, as 16, of the heel. The length of the flexible transverse section 13 corresponds substantially to the length of the straight edge 15 of the shoe heel, and the length of each of the flexible side sections 11 and 12 corresponds substantially to one-half of the curved edge of the heel. The opposed ends of the 80 sections of the body 10 are movably connected by means of three rings, as 17, 18, 19. These rings, as shown, are positioned so that the rings 17 and 18 will be at the upper parts of the corners of the heel, while the ring 19 will be at the upper part centrally of the curved edge of the heel when the device is applied to a shoe, and by employing rings of suitable sizes, in this manner the flexible band 10 may be adjustably 85 widened and narrowed in diameter when the rings are moved upwardly and downwardly on the shoe accordingly, in order to cause the band members to snugly fit the heel of the shoe.

100 To spaced parts centrally of the flexible side section 11 of the band 10 are held, re-

105 110

spectively, at 20 and 21, one of the ends of two flexible anti-skid or line elements 22 and 23, and the second ends of these line elements are held respectively, at 24 and 25, to spaced parts centrally of the flexible side section 12 of the band, though forms of the device may be made wherein only one of the elements are used. Both of these line elements, therefore, are disposed crosswise of the band, and the line elements are of sufficient lengths whereby they depend in somewhat parabolic fashion from the band member so as to be disposed upon the central portion transversely of the underside of the shoe heel. To the central part of the flexible transverse section 12 of the band 10 is held, at 26, one end of a third anti-skid or line element 27 having its second end parts held, at 28 and 29, to the central parts of the line elements 22 and 23, and this third line element is also of sufficient length to depend from the band for being disposed upon the underside of the heel from approximately its central part to and upon the straight edge of the heel. The line elements 22, 23, 27 may be made of metal chains or other flexible material, and as thus employed the line elements will serve to prevent the wearer of the device from slipping when walking on slippery highways by reason of the movements of the feet of the person when accidentally slipping being in forward directions, the line elements 22 and 23 being prevented by the line element 27 from moving under such strain toward the back of the shoe heel.

Serving as means to allow the band 10 with the flexible anti-skid or line elements 22, 23, 27 to be detachably fastened on a shoe, to the ring 17 is held one end of a flexible line or string 30, and to the ring 18 is held one end of a flexible line 31, while to the ring 19 is held one of the ends of two flexible lines or strings 32 and 33. The strings or lines 30, 31, 32, 33 are of lengths so that when guided upon the shoe to its instep the free ends of the strings will considerably overlap.

In practice one of the devices is preferably removably applied to the heel of each shoe of the wearer in a manner whereby the flexible chain band 10 circumscribes the heel of the shoe and so that the rings 17, 18, 19 will extend upwardly upon the shoe respectively at the corners and back of the curved edge of the heel. The flexible anti-skid or line elements 22, 23, 27 will then be disposed upon the underside of the heel, as illustrated and hereinbefore explained. These parts of

the device are detachably fastened on the shoe by the strings 30 and 31 being arranged upon the shoe for tying their free ends on the instep of the shoe, and by arranging the strings 32 and 33 on the shoe so that their free ends may be tied together also upon the instep of the shoe. By tightening the strings 30, 31, 32, 33 properly the band 10 and the line elements 22, 23, 27 will snugly fit the heel, thus providing a simple and efficient device whereby persons will be prevented from slipping when walking on slippery highways, as well as enabling the wearer to walk with ease and comfort in that the arrangement of the line or chain elements 22, 23, 27 provide a tread surface which will not tend to cause the ankles to accidentally turn.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:

As an article of manufacture, an anti-skid device, formed of a substantially triangular supporting band of three chain sections adapted to be removably disposed around the edge of a shoe heel and the ends of the said sections being connected by three rings, spaced chain elements having their ends held to central parts of two of the sections of the band and depending in parabolic fashion crosswise of the band for being disposed across the central part of the underside of the shoe heel, another chain element having one of its end portions held to the central parts of all of the first named chain elements as well as having its second end held to the central part of the third section of the band, two strings each having one of its ends fastened to one of the rings of the triangular band, and a pair of strings having one of their ends fastened to the third ring of the triangular band.

This specification signed and witnessed this 19th day of June A. D. 1919.

GEORGE H. RIVES.
